US0D1103687S

(12) **United States Design Patent** (10) **Patent No.:** **US D1,103,687 S**
(45) **Date of Patent:** **** Dec. 2, 2025**

(54) **COVER**

(71) Applicant: **Shuangma Plastic Manufacturing Inc.**, Zhejiang (CN)

(72) Inventor: **Cuihong Chen**, Zhejiang (CN)

(**) Term: **15 Years**

(21) Appl. No.: **29/907,044**

(22) Filed: **Jan. 3, 2024**

(30) **Foreign Application Priority Data**

Nov. 14, 2023 (CN) 202330743660.9

(51) **LOC (15) Cl.** **07-02**

(52) **U.S. Cl.**
USPC **D7/391**

(58) **Field of Classification Search**

(57) **CLAIM**

The ornamental design for a cover, as shown and described.

DESCRIPTION

FIG. 1 is a front and top view of a cover showing my new design;

FIG. 2 is a rear bottom perspective view thereof;

FIG. 3 is a front view thereof;

FIG. 4 is a rear view thereof;

FIG. 5 is a left view thereof;

FIG. 6 is a right view thereof;

FIG. 7 is a top plan view thereof;

FIG. 8 is a bottom plan view thereof; and,

FIG. 9 is a perspective view shown in use with environmental subject matter of an exemplary container.

The broken lines represent both parts of the article as well as environmental subject matter of an exemplary container.

None of the broken lines form part of the claimed design.

1 Claim, 9 Drawing Sheets
